UNITED STATES PATENT OFFICE.

EARL PERCIVAL COURtenay LOMAS, OF BUTTE, MONTANA.

TYPE-WRITER ATTACHMENT.

1,268,859.

Specification of Letters Patent. Patented June 11, 1918.

Application filed October 23, 1917. Serial No. 198,105.

To all whom it may concern:

Be known that I, EARL P. C. LOMAS, a citizen of the United States, and a resident of Butte, in the county of Silver Bow and State of Montana, have invented certain new and useful Improvements in Type-Writer Attachments, of which the following is a specification.

My invention is an improvement in type-writer attachments, and has for its object to provide mechanism in connection with the usual typewriter for automatically returning the carriage at the end of its movement during writing, wherein a spring motor is provided, wound and tensioned by the movement of the key bars on their striking movement, and wherein means is provided for restraining the operation of the motor until the end of the line is reached, other mechanism being provided, controlled by the movement of the carriage, for releasing the restraining means, the said restraining means being connected to the key locking means for releasing the restraining means when the key locking means is placed in operative position.

A further object of the invention is to provide trip mechanism operated by the carriage at the end of its movement during the writing for tripping the restraining means for the carriage returning mechanism.

A further object is to provide means controlled by the usual carriage releasing means for releasing the restraining means of the carriage returning means whenever the carriage is released in the usual manner.

A further object is to provide mechanism controlled by the movement of the carriage for preventing stoppage of the motor and the carriage by the release of the key locking means of the typewriter.

In the drawings:

Figure 1 is a rear view of a typewriter provided with the attachment;

Fig. 2 is an end view, with parts in section and with parts removed;

Fig. 3 is a detail of the release connection;

Fig. 4 is a top plan view of the typewriter;

Fig. 5 is a perspective view of one of the pawls;

Fig. 6 is a partial plan view of one end of the carriage and a portion of the frame;

Fig. 7 is an end view of Fig. 6;

Figs. 8 and 9 are perspective views of details of the mechanism for operating the spacing mechanism;

Fig. 10 is a detail perspective view of a portion of the spring motor and its controlling mechanism;

Fig. 11 is a partial perspective view showing a portion of the carriage;

Fig. 12 is a section on the line 12—12 of Fig. 11; and

Fig. 13 is a section on the line 12—12 of Fig. 12.

The present embodiment of the invention is shown in connection with an Underwood typewriter, indicated at 1, and the improved mechanism comprises a spring which is arranged within a cylindrical casing 3, one end of the spring being secured to the casing and the other to a shaft 4 which is journaled at the right end of the typewriter and at the rear thereof, in the same manner as the usual spring 5 for running the carriage to the left. A crank 6 is connected with the shaft at the opposite end from the spring casing, to permit the spring to be wound, and a ratchet wheel 7 is secured to the shaft, with which co-operates an escapement pawl 7^a for holding the spring under tension.

The type bars 8 of the typewriter, when they are swung upwardly into writing position by the key levers 9, strike an arc shaped ring 10, and move the said ring rearwardly. This ring bears against the angular ends of a pair of connected bars 11, which are pivoted to the tops of levers 12 rigid with a shaft 13 journaled in the typewriter casing at the rear thereof and form a part of the typewriter. The motion of these bars 11 rearwardly is utilized to store up power to return the carriage, that is, to wind the spring 2. This spring, which is the motor for returning the carriage, is wound to a tension which exceeds the tension in the primary motor 5 by a few turns, so that when the restraining means for preventing the operation of the spring 2 is released, the motor 2 will return the carriage.

The motor casing 3 is connected to the carriage by a band 14, the band winding upon the motor casing when the carriage is drawn to the right. A ratchet wheel 15 is rigid with the motor casing, and the teeth of this ratchet wheel are engaged by pawls 16 and 17, the said pawls being the actuating

pawl and the holding pawl, respectively. The pawl 16 is pivoted to one of the arms of a bell crank lever 18, and the other arm of the lever is pivoted to one of the bars 11 in such manner that when the bar is moved rearwardly the pawl 16 will be moved downwardly. The pawl 17 is pivoted between lugs 19 on the typewriter casing, and springs 20 are provided for pressing the pawls toward the ratchet wheel.

It will be evident from the description that every time a letter is struck and the bars 11 move rearwardly, the motor 5 will be advanced a distance of one tooth, and when the carriage has reached the end of its movement to the left, that is, during the writing, the spring 2 will have been wound to a tension sufficient to return the carriage to position of commencement. The spring 2 is released by means of a yoke comprising a body 21 and arms 22, the arms being pivoted to lugs 23 on the typewriter casing, and each arm has an extension 24 passing just inside the adjacent pawl and adapted to engage a cam 25 on the pawl to force the said pawl rearwardly to disengage it from the ratchet wheel. This yoke is swung to release the pawls by means of the locking bar 26 for the keys.

When the end of the line is reached, with the typewriter in question, this locking bar is swung forwardly into the dotted line position of Fig. 2, beneath catches or hooks 27 on the key levers, and the key levers are prevented from downward movement by the locking bar. A link 28 connects the locking bar to the body of the yoke, that end of the link adjacent to the locking bar being slotted, as shown at 29, so that the locking bar may have a limited movement with respect to the link for a purpose to be presently described. It will be evident that when the locking bar is moved forwardly into the dotted line position of Fig. 2 the link will be moved in the same direction and will swing the yoke to cause the extensions 24 to engage the cams 25 and release the pawls, and the spring 2 will immediately come into operation to return the carriage.

Means is provided in connection with the usual release lever for the carriage for releasing the pawls 16 and 17 and the motor 2. The release lever 30 is connected to the yoke by a link 31. This link has a notch 32 at its upper end which engages a rod 33 forming a part of the release mechanism, and the opposite end of the link has an inclined slot or passage 34 in which the yoke body 21 engages. The upper end of the slot or passage is open in order that it may be engaged with the yoke body, and the link is guided by headed pins 35 on the typewriter, which engage longitudinally extending slots in the link. This slot or passage 34 is so inclined that when the rear end of the lever

30 is moved upwardly to release the carriage the link 31 will be moved upwardly, and the body of the yoke will be pushed forwardly, thus swinging up the extensions 24 and releasing the pawls. With this arrangement, whenever the carriage is released at any point in its travel, the motor 2 will also be released to permit the typist to return the carriage.

When the carriage moves to the left and the end of the writing line is reached, the key locking mechanism, that is, the locking bar 26, is moved forwardly to locking position. This is brought about by a lug 36 on the carriage, which rides upon a species of cam plate 37 which is adjustably connected with a rack bar 38 on the typewriter frame. A shaft 39 is then oscillated and this shaft is connected with the locking bar in such manner that the locking bar will be moved forwardly. When, however, the carriage begins to return to the right, at once the lug 36 passes off the cam plate 37, the locking bar is released, that is, the said bar is swung rearwardly, and were no means provided the pawls 16 and 17 would be permitted to engage the ratchet wheel 15, checking the motor and the carriage. To prevent this, I provide a locking lever 40 which is pivoted at 41 intermediate its ends, and one end of the lever is adapted to engage a notch 42 in the link 28 before mentioned. When the lever is in engagement with the notch it will be obvious that the link cannot move rearwardly, and since the connection between the locking bar and the link is a lost motion connection, the locking of the link does not interfere with the unlocking movement of the locking bar. This locking lever 40 remains in locking position until it is released by the movement of the carriage as it reaches the end of its movement to the right, and precisely the same mechanism is provided for oscillating the shaft 39 to release the locking lever as that which is provided to release the key locking bar. The said mechanism comprises a cam plate 43 which is adjustably connected with the rack bar 38. This cam plate is a part of a slide 44 which is mounted to slide upon the shaft 39, and is locked to the rack bar at any desired point by means of a lever 45, the said lever having a toothed pawl 46 for engaging the rack bar to hold the slide at the point desired. By this means the cam plate 43 may be placed wherever desired at any point in the movement of the travel of the carriage. The shaft 39 has an arm 47, and this arm has an angular portion which engages the outer end of the lever 40 in such manner that when the shaft 39 is oscillated by the downward movement of the rack bar 38 the angular portion will swing the lever to disengage it from the notch 42. The lever 40 engages the notch by gravity, the pivotal connec-

tion being nearer that end of the lever engaged by the arm 47 than that end which engages the link 28.

The operation of the above described mechanism is as follows: The parts being properly arranged and the spring 2 under proper tension, which may be brought about by means of the crank 6, the typewriter is operated in the usual manner to write. As the keys are operated the spring 2 is placed under tension, the wheel 15 advancing one tooth for every key struck and for each movement of the spacing bar. As the carriage nears the end of its travel to the left, the lug 36 will engage the cam plate 37 and the locking bar 26 will be swung into locking position, carrying forward the link 28, and swinging the yoke 21-22 to release the pawls. The link 28 is locked in its forward position, and, with the pawls released by means of the locking lever 40, the motor 2 now moves the carriage to the right, that is, returns it to commencing position, the lug 36 engages the cam plate 43 and oscillates the shaft 39 to cause the arm 47 to release the locking lever 40, thus permitting the link to move forward and the yoke to move into inoperative position. The springs 20 have sufficient resiliency to return the link and yoke to normal inoperative position. In case it should be desired to return the carriage before reaching the end of the line, or in case it is desired to move the carriage in either direction, that is, to release it for any purpose, it is released in the usual manner by swinging the lever 30 which is the release key for the carriage. When this key is swung the link 31 swings the yoke 21-22 to release the pawls.

40 The usual line spacing mechanism 48 is utilized in the present case. A sleeve 49 is journaled on the carriage at 50, and this sleeve has at one end a radial arm 51. At the opposite end it has a tangential arm 52, and this tangential arm is in position to engage the said line spacing mechanism 48 to operate the same when the arm 51 is swung to the left. An elbow lever 53 is pivoted to a fixed portion of the typewriter, as indicated at 54, and one of the arms of the elbow lever normally rests upon a fixed portion 55 of the typewriter frame. The other arm of the elbow lever extends upwardly into the path of movement of the arm 51, and when 55 the carriage is passing to the left the arm 51 and the upstanding arm of the elbow lever 53 will move idly past each other. When, however, the carriage starts to move toward the right, the arm 51, which has 60 passed the upstanding arm of the lever, will engage behind the said upstanding arm, and since this upstanding arm of the elbow lever cannot swing in the opposite direction the arm 51 must swing as indicated in dotted lines in Fig. 6, and the arm 52 will operate

the line spacing mechanism of the typewriter.

The horizontal arm of the elbow lever 53 holds the parts in the position shown in Fig. 7 by gravity. After the carriage begins its 70 reverse movement to commencing position the line spacing mechanism will be operated to advance the paper another line, and whether this advancement is one space, two spaces or three spaces, it is controlled by the 75 line spacing mechanism in the usual manner.

The locking bar 26 is moved beneath the catches or hooks 27 by an arm 60 depending from the shaft 39. This arm engages an upstanding arm 61 on a shaft 62 journaled below the keys, and the shaft 62 supports the bar 26 by means of upstanding arms 63. When the shaft 39 is oscillated by the mechanism shown in Fig. 11, the arm 60 is swung forwardly, swinging forwardly the arm 61 85 and oscillating the shaft 62 in a direction to move the locking bar 26 beneath the hooks or catches 27.

I claim:

1. In combination with a typewriter, a 90 spring for returning the carriage, means controlled by the striking of the keys during writing for placing the spring under tension, means for restraining the operation of the spring, means for releasing the restraining means controlled by the locking of the keys at the end of the line, and auxiliary locking means for holding the restraining means in released position when the keys are unlocked and controlled to release 95 100 at the end of the return movement of the carriage.

2. In combination with a typewriter, means for returning the carriage, means for restraining the operation of the returning 105 means, and means controlled by the key locking means at the end of a line for releasing the restraining means.

3. In combination with a typewriter and the carriage release, means for returning 110 the carriage, means for restraining the operation of the returning means, means controlled by the key locking means at the end of a line for releasing the restraining means, and means controlled by the carriage release 115 for releasing the restraining means.

4. In combination with a typewriter, a spring for returning the carriage, means controlled by the depression of the keys for placing the spring under tension, means for restraining the operation of the returning 120 spring, and means controlled by the locking of the keys at the end of a line for releasing the restraining means.

5. In combination with a typewriter and the carriage release, a spring for returning 125 the carriage, means controlled by the depression of the keys for placing the spring under tension, means for restraining the operation of the returning spring, means con- 130

trolled by the locking of the keys at the end of a line for releasing the restraining means, and means controlled by the carriage release for releasing the restraining means.

6. In combination with a typewriter and the carriage release, a spring for returning the carriage to position for commencing a line, means controlled by the downward movement of the keys and spacing bar for 10 winding the spring, a holding pawl for the spring for preventing reverse movement thereof, a common means for releasing the pawl and for disconnecting the keys from the spring when the keys are locked at the 15 end of a line, a connection between the said means and the release key for the carriage for operating the said means to release the spring when the carriage is released, auxiliary means for holding the said common 20 releasing means in operative position after the keys are unlocked when the carriage begins to return, and means controlled by the carriage as it reaches the end of its move-

ment toward commencing position for releasing the said auxiliary means.

7. In combination with a typewriter, means for returning the carriage, means for restraining the operation of the returning means, means controlled by the key locking means at the end of a line for releasing the restraining means, and means controlled by the movement of the carriage as it begins its return movement for operating the line spacing mechanism.

8. In combination with a typewriter, means for returning the carriage, means for restraining the operation of the returning means, means controlled by the key locking means at the end of a line for releasing the restraining means, means controlled by the carriage release for releasing the restraining means, and means controlled by the movement of the carriage as it commences its return movement for operating the line spacing mechanism.

EARL PERCIVAL COURTENAY LOMAS.
